RAILWAY SWITCH OPERATING APPARATUS

Walter L. Stout, Swissvale, Pa., assignor to The Union Switch & Signal Company, Swissvale, Pa., a corporation of Pennsylvania

Application March 2, 1934, Serial No. 713,699

16 Claims. (Cl. 246—358)

My invention relates to railway switch operating apparatus, and particularly to manually controlled switch operating apparatus for switches of the type which are designed to be trailed.

5 Specifically, my present invention relates to
improvements in railway switch operating appa-
ratus of the type disclosed and claimed in Let-
ters Patent of the United States, No. 1,976,830,
granted to Herbert L. Bone and William C. Mc-
10 Whirter, on Oct. 16, 1934, and also to improve-
ments in railway switch operating apparatus of
the type disclosed and claimed in an application
for Letters Patent of the United States, Serial
No. 693,626, filed by Herbert L. Bone on Oct. 14,
15 1933.

One object of my invention is to provide apparatus of the type described including means for locking the switch in both extreme positions for facing point moves over the switch in such manner that if a train trails the switch when the switch occupies either extreme position, the switch will become automatically unlocked by means mechanically actuated by the wheels of the train, and will remain unlocked until the train is completely past the switch, after which the switch will again become locked in the extreme position which it previously occupied.

Other objects of my invention will become apparent as the description proceeds.

In the accompanying drawings, Fig. 1 is a top plan view showing a railway switch A provided with one form of switch operating apparatus embodying my invention. Fig. 2 is an enlarged view partly in section and partly in elevation, of the switch operating mechanism B forming part of the apparatus shown in Fig. 1. Fig. 3 is a sectional view taken substantially on the line III—III of Fig. 2. Fig. 4 is an enlarged front elevational view of a portion of the apparatus shown in Fig. 1. Fig. 5 is a top plan view showing a modified form of the apparatus illustrated in Fig. 1. Fig. 6 is a front elevational view of a portion of the apparatus shown in Fig. 5.

Similar reference characters refer to similar parts in each of the several views.

Referring first to Fig. 1, the reference character 50 A designates a railway switch comprising, as usual, two fixed rails 1 and 1^a and two movable rails 2 and 2^a. The fixed rails 1 and 1^a are laid on tie plates 3 and are secured to crossties 4 in the usual manner. The movable rails 2 and 2^a are fastened together by a front rod 5, a head rod 6, a bridle 55

rod 7 and a tie rod 8, and may be moved into a normal or reverse position by means of an operating rod 9 which is connected with the head rod 6 through the medium of the usual switch basket 10. When the switch occupies its normal position in which it is shown in Fig. 1, the movable rail 2 engages the fixed rail 1, and the movable rail 2^a is spaced a slight distance from the fixed rail 1^a. When the switch is reversed, however, the movable rail 2^a then engages the fixed rail 1^a, and the movable rail 2 is spaced from the fixed rail 1. 5

Associated with the switch A is a switch operating mechanism B comprising a main casing 11 which is bolted or spiked to the ties 4 adjacent the outer side of the rail 1, and an auxiliary casing 12 which is bolted to the left-hand end of the casing 11. The main casing 11 is provided with a removable cover 13, while the auxiliary casing 12 is provided with a removable cover 14. 20

Extending downwardly through the main casting 11 is a rotatable spindle or switch actuating shaft 16, and attached to the lower end of this shaft is an adjustable crank 17 which is pivotally connected with the previously described operating rod 9, the parts being so proportioned that rotation of the shaft 16 through an angle of approximately 90° will move the switch between its normal and reverse positions. 25

The lower portion of the shaft 16, that is, the portion within the casing 11, is made round, and is journaled in a bearing 18 provided in the bottom of the casing 11, and in a star block 19, which in turn, is journaled in a bearing 20 formed in the top of the casing 11. The portion of the shaft 16 above the top of the star block bearing, however, is made square, and has a somewhat smaller cross-sectional area than the lower portion of the shaft. 30 35

Secured to the square portion of the shaft 16 is a square sleeve 21, and slidably mounted on this sleeve is an outer sleeve 22 which is provided with a square opening to receive the inner sleeve so that both sleeves and the shaft are constrained to rotate together.

When the outer sleeve 22 occupies its lowermost position on the inner sleeve, in which position it is shown in the drawings, a squared portion 23 formed on the lower end of the outer sleeve 5 enters a squared recess or socket 24 formed in the upper end of the star block 19, and under these conditions, the outer sleeve, and hence the shaft 16, is connected with the star block, so that any rotation of the shaft will cause corresponding 5

rotation of the star block. When, however, the outer sleeve 22 is moved to an upper position on the inner sleeve, the squared portion 23 on the lower end of the outer sleeve becomes disengaged 5 from the socket 24 in the star block, and the two sleeves and the shaft are then free to rotate as a unit independently of the star block.

The outer sleeve 22 is arranged to be moved between its two extreme positions by means of a 10 hand lever 27 which also serves as a means for rotating the switch actuating shaft 16 between its two extreme positions. This lever is bifurcated at one end, and the bifurcations thereof are disposed on opposite sides of a squared portion 15 formed at the upper end of the outer sleeve, and are pivoted at their free ends on a pin 28 mounted in a lug 29 formed on the inner sleeve 21. Each bifurcation extends between a pair of lugs 30 which are secured to the associated side of the outer sleeve 22, only one pair of lugs being visible 20 in the drawings. The parts are so proportioned that when the lever 27 is rotated about the pin 28 to the depending position in which it is shown in the drawings, the outer sleeve 22 will be moved 25 to its lowermost position on the inner sleeve, but that, when the lever is rotated about the pin 28 to a substantially horizontal position, the outer sleeve will then be moved to its upper position on the inner sleeve. It follows that the switch actuating shaft 16 will be connected with, or disconnected from, the star block 19 according as the 30 lever 27 occupies its depending or its horizontal position, and that, when the lever occupies its horizontal position, the shaft 16 may be rotated 35 between its two extreme positions to move the switch points to their corresponding extreme positions by rotating the lever about the axis of the shaft, without causing rotation of the star block.

When the hand lever 27 occupies its depending 40 position, which position is its normal position, it may be locked in this position by placing a padlock 51 or other suitable locking device through a hole 52^a formed in the outer end of a lug 52 which is fastened to the outer sleeve 22, and which passes 45 through a suitable slot 53 in the lever 27.

A suitable signal, here shown as a pair of vanes 31, positioned 90° with respect to each other in plan view, is fastened to the upper end of the switch actuating shaft 16, and serves to accurately indicate at all times the position of the 50 switch.

The star block 19 is constantly biased to the position in which it is shown in the drawings by means of two biasing devices 32 and 33 which are 55 disposed on opposite sides of the star block, as best seen in Fig. 3. These biasing devices are similar, and a description of one will therefore suffice for both. Referring particularly to the biasing device 32, this biasing device comprises a rod or 60 bolt 34 supported at one end in a wall of the casing 11, and at the other end in an upright support 35 provided on the bottom of the casing 11. Two sleeves 36 and 37 provided with annular flanges 36^a and 37^a, respectively, are slidably 65 mounted on the bolt 34 with their flanges 36^a and 37^a facing each other, and positioned on the bolt between these sleeves is a coil spring 38 which biases these sleeves to the position in which the outer end of the sleeve 36 engages one of a pair 70 of thrust washers 39 interposed between the sleeve and the side wall of the casing 11, and in which the outer end of the sleeve 37 engages one of a pair of thrust washers 40 interposed between this sleeve and the support 35. Surrounding the 75 sleeves 36 and 37 and the spring 38 is a third

sleeve 41 having a flange 42 at one end which engages the outer side of the flange 37^a of the sleeve 37, and a removable flange 43 at the other end which engages the outer side of the flange 36^a of the sleeve 36. An upwardly projecting lug 44 is secured to the outer sleeve 41 as shown in Fig. 3.

The lug 44 on the biasing device 32 extends upwardly between two rollers 45 and 46 which are journaled between suitable spaced lugs formed on the star block 19, and the lug 44 on the outer sleeve of the biasing device 33 similarly extends upwardly between two rollers 49 and 50 which are also journaled between the lugs on the star block, the four rollers 45, 46, 49 and 50 being disposed at the four corners of a rectangle. The 15 lugs 44 are adapted to slide along ribs 44^a cast on the side of casing 11.

With the biasing devices constructed and connected with the star block in the manner just described, it will be apparent that rotation of the 20 star block 19 in either direction from the position shown will cause the lugs 44 on the outer sleeve 22 of the two biasing devices 32 and 33 to rotate in opposite directions, thus compressing the springs within the biasing 25 devices. It follows, that when the star block has been rotated away from the position shown, as soon as the force which caused the rotation of the star block is removed, the springs will act to restore the star block to the position shown.

For reasons which will become apparent as the description proceeds, it is desirable to prevent the biasing devices from returning the star block to the position shown at too rapid a rate after the star block has been moved away from this position, without interfering with the rotation of the star block away from the position shown. For this purpose, the star block is pivotally connected with the piston rod 55 of a dash pot or buffering device 56, the cylinder 57 of which is pivotally attached to the right-hand wall of the casing 11 by means of a pin 58 and a lug 59. The buffering device 56 forms no part of my present invention, and may be of any suitable type which will allow free and unrestricted movement of the piston rod 40 out of the cylinder, but which will retard movement of the piston rod into the cylinder. As here shown, this buffering device is similar in all respects to the buffering device shown and described in Letters Patent of the United States No. 1,830,803, 50 granted to William C. McWhirter, on Nov. 10, 1931, for Railway switch operating apparatus, and it is believed to unnecessary therefore to describe it in detail here.

Reciprocably mounted in the bottom of the 55 casing 11 is a locking device 60 which in the particular embodiment of my invention here illustrated, comprises two spaced end members 60^a and 60^b (see Fig. 3) connected together by means of a pair of spaced stud bolts 60^c and 60^d. The 60 left-hand end member 60^a is provided on its left-hand side with an integral rectangular locking plunger 60^e, while the right-hand end member 60^b is provided with a centrally located hole 60^g.

The locking plunger 60^e is mounted to slide in 65 a guideway 61 formed on the bottom of the casing 11, and is adapted to cooperate with a lock rod L which is slidably mounted in the casing 11 at right angles to the locking plunger. The lock rod L is of standard construction and comprises 70 two longitudinally adjustable bars 63 and 64 attached at one end to the front rod 5 of the switch A, and provided with two sets of registering notches, the notches of the one set each being designated by the reference characters 65^a, and 75

the notches of the other set each being designated by the reference characters 65^a. The registering notches 65^a and 65^b are so disposed in the bars 63 and 64, and the bars are so adjusted, that the notches 65^a will align with the locking plunger 60^c when and only when the switch occupies its normal extreme position in which it is shown in the drawings, and that the notches 65^b will align with the locking plunger when and only when the switch occupies its reverse extreme position.

The locking device 60 is arranged to be moved, in a manner which I will describe hereinafter, between a left-hand extreme position in which the locking plunger enters the notches 65^a or 65^b in the lock rod L, and a right-hand extreme position in which the locking plunger is withdrawn from both sets of notches, and it will be apparent that when the locking plunger occupies its left-hand extreme position the switch will be securely locked in the extreme position which it then occupies, but that when the locking plunger occupies its right-hand extreme position, the switch will then be unlocked.

The bolt members 60^a and 60^b of the locking device 60 are slidably mounted adjacent their right-hand ends in suitable lugs 66 and 67, respectively, which project upwardly from the bottom of the main casing 11, and surrounding each bolt member between the end member 60^a and the associated lug 66 or 67 is a partly compressed coil spring 68 which constantly biases the locking device 60 to its left-hand extreme position.

A bell crank lever 69 is pivoted on a pin 70 mounted in a pair of spaced lugs 71 projecting from the side of the casing 11, and the one arm 69^a thereof extends downwardly and is provided at its lower end with a rounded portion 69^b which cooperates with the left-hand side of the end member 60^a in a manner which will be described hereinafter. The other arm 69^c of the bell crank lever 69 extends toward the right and is pivotally connected at its free end by means of a pin 72 and an adjustable screw jaw 73, with the lower end of a vertical connecting rod 74.

The connecting rod 74 is shaped as shown, and comprises, in addition to the screw-threaded lower end which receives the screw jaw 73, an integral offset portion 74^a which is rectangular in cross-section. This offset portion extends upwardly with a sliding fit through a rectangular guideway 75 formed in the top wall of the casing 11, and is provided at its upper end with a lateral extension 74^b which overlies and cooperates with, an annular flange 77 formed on the sliding sleeve 22 directly above the squared portion 23. A two-piece collar 78 is bolted to the sliding sleeve 22 some distance above the annular flange 77 and lateral extension 74^b, and extending downwardly from this collar is an integral frusto-conical hood 79 which completely encloses the upper part of the offset portion 74^a of the connecting rod 74 and the annular flange 77, thus protecting these parts from dirt, moisture, snow, etc.

The lower end 74^c of the offset portion 74^a of the connecting rod 74 overlies and cooperates with a cam member 80 formed integrally with the star block 19. This cam member has a semi-circular periphery and its upper surface curves downwardly from each end toward the center, as shown in Fig. 2. Only one half of this cam member is visible in Fig. 2, because the other half is directly back of the half shown, but the half which is not visible is similar to the half which is visible.

The parts are so proportioned that when the

sliding sleeve 22 occupies its lowermost position, and the star block 19 occupies the position to which it is biased by the biasing devices 32 and 33, as shown in the drawings, the connecting rod 74 will move by gravity to the position in which it is shown in the drawings, which position I shall hereinafter refer to as its "lowermost" position. The parts are further so proportioned that when the connecting rod 74 occupies its lowermost position, the underside of the lateral extension 74^b of the connecting rod will engage the upper side of the annular flange 77, the lower end 74^c of the offset portion 74^a will engage the upper face of the cam member 80 at the lowest point of the cam face, and the bell crank lever 69 will be rotated to a position in which the rounded portion 69^b would engage the left-hand side of the end member 60^a of the locking device 60 if the locking device were then moved to its extreme left-hand position by the biasing springs 68.

The locking device 60, in addition to being operatively connected with the sliding sleeve 22 and the star block 19 in the manner just described, is also operatively connected with the previously described tie rod 8 by means of linkage embodying my present invention, which linkage I will now describe. As here shown, this linkage includes a plunger bolt 81 (see Fig. 2) which extends with some clearance through the hole 60^c in the end member 60^b of the locking device 60, and the head of which plunger bolt cooperates with the left-hand side of the end member 60^b. The threaded right-hand end of the plunger bolt 81 is adjustably connected by means of a turn buckle 82 (see Fig. 1), with one end of a link 35 30, the other end of which is secured to a U-shaped member 84 (see Fig. 4). The U-shaped member 84 is disposed with its one leg 84^a directly above the other leg 84^b, and is guided to slide longitudinally on the bed plate 15 by means of 40 rollers 85 mounted on suitable pins which are journaled at their lower ends in the bed plate, and at their upper ends in a top plate 86 which is bolted to the bed plate in parallel spaced relation, as shown in Fig. 4. Extending at right angles to the U-shaped member 84 between the legs 84^a and 84^b thereof, and guided for longitudinal sliding movement by means of the same rollers 85 which guide the U-shaped member 84, is a cam plate 87 provided with a cam slot 88. 50 The cam slot 88 is formed with a portion at each end which is inclined to the direction of movement of the cam plate, and with an intermediate connecting portion which is parallel to the direction of movement of the cam plate, and this 55 cam slot cooperates with a roller 89 fastened to a pin 90 which is journaled at its opposite ends in the legs of the U-shaped member 84. The cam plate 87 is operatively connected by means of a bar 91 with one end of a lever 92 which is pivotally mounted intermediate its ends in a crank stand 93, and which is operatively connected at its free end with the previously described tie rod 8, by means of an operating rod 94 and a standard switch basket 95.

The parts are so proportioned that if the motion plate 87 is moved upwardly to the extreme position in which the roller 89 engages the lower end of the inclined lower portion of the cam slot 88, or downwardly to the extreme position in which the roller engages the upper end of the inclined upper portion of the cam slot, the plunger bolt 81 will be moved toward the left far enough to permit the locking device to move to the extreme position to which it is biased by the springs 75.

68, but that, if the motion plate is moved to any position in which the roller 89 occupies the straight central portion of the cam slot, the plunger bolt 81 will then be moved toward the right to a position in which its head will engage the end member 60^b of the locking device and move the locking device to its unlocking position. The parts are further so proportioned that when the movable rails of the switch are moved to their proper normal positions, the motion plate will not be moved to its extreme upper position, but will be moved toward this position far enough to cause the roller 89 to enter the inclined lower portion of the cam slot and move the plunger bolt 81 toward the left to a position in which it will arrest the movement of the locking device by the biasing springs 68 when the locking device has been moved to what I shall term its "proper" locking position, and that when the movable rails are moved to their proper reverse positions the motion plate will not be moved to its extreme lower position, but will be moved toward this latter position far enough to cause the roller 89 to enter the inclined upper portion of the cam slot and move the plunger bolt toward the left to the same position to which it is moved when the movable rails of the switch are moved to their proper normal positions. For convenience I shall hereinafter refer to the position which the motion plate 87 occupies when the movable rails occupy their normal positions as the "normal" position of the motion plate, and the position which the motion plate 87 occupies when the movable rails of the switch occupy their proper reverse positions as the "reverse" position of the motion plate.

The apparatus will usually also be provided with a circuit controller C including means for indicating when the locking device 60 is in its proper locking position for either facing point or trailing moves over the switch in both extreme positions of the switch, and means for indicating when the movable rails which should be in close engagement with the associated fixed rail in either extreme position of the switch is in proper engagement with such fixed rail. This circuit controller is located in the casing 12 of the mechanism B and may be of any suitable type. As here shown, this circuit controller is similar in all respects to the circuit controller shown in the previously referred to copending Bone and McWhirter application, Serial No. 668,198, and since it forms no part of my present invention, it is deemed unnecessary to describe it herein.

The operation of the apparatus, as a whole, is as follows: As shown in the drawings, the movable rails of the switch A occupy their normal extreme positions and the hand lever 27 is locked in its depending position by means of the padlock 51. Under these conditions, the sliding sleeve 22 is held in its lowermost position on the inner sleeve 21, and the star block 19 is accordingly connected with the switch actuating shaft 16, so that the biasing devices 32 and 33 are effective to bias the movable rails of the switch to their normal positions. Furthermore, under these conditions, the connecting rod 74 is held in its lowermost position by gravity, and the cam plate 87 is held in its normal position by the linkage which connects the cam plate with the tie rod 8; and as a result, the locking device 60 is held in its locking position by the biasing springs 68, so that the switch is securely locked in its normal extreme position.

I will now assume that it is desired to reverse

switch A. To do this, padlock 51 is first removed from the hole 52^a in the lug 52 to unlock the hand lever 27, and the hand lever 27 is then raised to its horizontal position. This preliminary movement of the hand lever raises the sliding sleeve 22 from its lowermost position in which it is shown in the drawings to its uppermost position, and as was previously pointed out, when the sliding sleeve 22 is moved to its uppermost position, the squared portion 23 on the lower end of this sleeve becomes disengaged from the socket 24 in the upper end of the star block 19, thus disconnecting the star block, and hence the biasing devices 32 and 33 and the buffering device 56 from the switch actuating shaft 16, so that the switch actuating shaft 16 is then free to rotate without any opposition from the biasing and buffering devices. Furthermore, when the sliding sleeve 22 is moved to its uppermost position, the annular flange 77 on the lower end of this sleeve cooperates with the lateral extension 74^b on the connecting rod 74 to move the connecting rod 74 to its uppermost position, and this movement of the connecting rod, in turn, acts through the bell crank lever 69 to move the locking device 60 from its locking position in which it is shown in the drawings to an unlocking position in which the locking plunger 60^c is completely withdrawn from the notches 65^a in the lock rod L, thus unlocking the switch. The biasing and buffering devices now being disconnected from the switch actuating shaft, and the switch being unlocked, the hand lever 27 is next rotated, in the horizontal plane which it then occupies, through an angle of approximately 90° in a counter-clockwise direction. This intermediate movement of the hand lever rotates the switch actuating shaft 16 to the extreme position opposite to that in which it is shown in the drawings, thereby reversing the movable rails of the switch in the manner previously described. As the movable rails move to their reverse position, the cam plate 87 is moved from its normal position in which it is shown in the drawings to its reverse position, thus causing the plunger bolt 81 to first move toward the right from the position in which it is shown in the drawings, and then to be restored to the position in which it is shown in the drawings. This movement of the plunger bolt, under these conditions, however, has no effect on the remainder of the apparatus since the locking device is then held in its unlocking position by the bell crank lever 69 in the manner previously described. The switch points now being fully reversed, the hand lever 27 is next restored to its depending position. This final movement of the hand lever, of course, restores the sliding sleeve 22 to its lowermost position, thus reconnecting the star block 19 with the switch actuating shaft, and at the same time permitting the connecting rod 74 to return to its lowermost position. As the connecting rod 74 returns to its lowermost position, the biasing springs 68 move the locking device 60 toward the left from its unlocking position to its locking position in which the locking plunger 60^c now enters the aligned notches 65^b in the lock rod, thus securely locking the switch in its reverse position. After the hand lever has been restored to its depending position, it may, if desired, be relocked in this position by again inserting the padlock 51 in the hole 52^a in the lug 52.

If, when the switch has been moved to its reverse position, in the manner just described, it is desired to restore the switch to its normal position, the hand lever 27 is first raised from its de-

pending position to its horizontal position, and is then rotated in a clockwise direction through an angle of 90° as viewed in Fig. 1, and is finally restored to its depending position and relocked in this position. The operation of the various parts of the apparatus, under these conditions, is just the reverse of that described above, and will be readily understood from the foregoing description and from an inspection of the drawings without further description.

I will now assume that the parts are in their normal positions, as shown in the drawings, and that a train trails the switch. As the leading wheels of the train roll along the fixed rail 1 and movable rail 1^a, the movable rails 2 and 2^a are forced over laterally, but before a sufficient force is developed at the points of these rails to overcome the opposing force of the biasing devices 32 and 33 and cause the point of the movable rail 2 to move out of engagement with the fixed rail 1, the movable rails being somewhat resilient become bent, so that with the usual standard split switch the tie rod 8 will be moved upwardly as viewed in Fig. 1, three-fourths of an inch or more. This movement of the tie rod 8 acts through the operating rod 94, lever 92 and bar 91 to move the cam plate 87 downwardly from its normal position in which it is shown in the drawings to a position in which the roller 89 is forced out of the inclined lower end of the cam slot 88 and into the straight central portion of the cam slot, and as was previously pointed out when the roller 89 is forced out of the inclined lower end of the cam slot and into the central portion of the cam slot, the link 83 and plunger bolt 81 are moved to the right far enough to move the locking device 60 from its locking position to its unlocking position, in which latter position the locking plunger 60^a is completely withdrawn from the aligned notches 65^a in the lock rod, thus unlocking the switch. As a result, when the leading wheels of the train have reached the positions in which a sufficient force is developed at the points of the movable rails to cause the point of the movable rail 2 to move out of engagement with the fixed rail 1, the movable rails will be unlocked, and the movable rails will therefore be forced away from their normal positions by the wheels of the train in exactly the same manner as they would be if no point lock were provided. The movement of the movable rails away from their normal positions acts through the operating rod 9 and crank 17 to rotate the switch actuating shaft 16 in a counter-clockwise direction, and this rotation of the shaft 16, in turn, rotates the associated sleeves 21 and 22 and the star block 19 in the same direction. The rotation of the star block 19 actuates the biasing devices 32 and 33 in the manner previously described, so that these biasing devices now tend to constantly restore the movable rails to their normal position. The rotation of the star block 19 also actuates the buffering device 56 which, as was previously pointed out, permits free and unrestricted rotation of the star block in the direction to compress the springs of the biasing devices 32 and 33, but acts to retard movement of the star block by the biasing devices. It will be seen, therefore, that the buffering device 56 will not oppose the movement of the movable rails away from their normal position, but will prevent too rapid movement of the movable rails toward their normal position by the biasing devices 32 and 33, thus preventing the quick return of the movable rails to their normal position between the passage

of the successive wheels of the train. The rotation of the star block 19 further causes the cam 80 to rotate, which rotation, due to the shape of the cam 80, forces the connecting rod 74 upwardly from its normal position. The parts are so proportioned that this upward movement of the connecting rod will rotate the bell crank lever 69 in a counter-clockwise direction to such a position that, if the switch points are forced to their full reverse position by the trailing train, thereby causing the lock rod L to be moved to the position in which the notches 65^b align with the locking plunger 60^c of the locking device 60, and the plunger bolt 81 to be moved to its normal position due to the roller 89 being forced into the inclined upper end of the cam slot 88 in the motion plate, the bell crank lever 69 will engage the locking device and will prevent the biasing springs 68 from moving the locking device to its locking position. After the train has completely passed the switch, the displacing force of the wheels will, of course, be removed, and the springs of the biasing devices 32 and 33 will then slowly return the movable rails to their normal position. During the return movement of the movable rails, the star block 19 will, of course, slowly return to the position in which it is shown in the drawings, thus permitting the connecting rod 74 to return by gravity to its lowermost position. When the movable rails have returned to within a short distance of their full normal position, the roller 89 will start to move into the inclined lower end of the cam slot 88 in the cam plate 87, and as a result, during the balance of the return movement of the movable rails the plunger bolt 81 will be moved toward the left so that when the switch reaches its full normal position, the plunger bolt will be restored to its normal position in which it is shown in the drawings. As the plunger bolt moves toward the left, the biasing springs 68 move the locking device toward its normal position, and since there is no deflection of the movable rails under these conditions, the locking plunger will be moved into engagement with the side of the lock rod before the movable rails have reached their full normal position in which the notches 65^a in the lock rod align with the locking plunger. As a result, after the locking plunger has once moved into engagement with the side of the lock rod, the locking plunger will slide along the side of the lock rod until the notches 65^a move into alignment with the locking plunger, at which time the energy stored in the compressed springs 68 will force the locking plunger to its normal locking position thus restoring the switch to its normal locked condition. When the switch has been restored to its normal locked condition, all parts will then be restored to their normal positions in which they are shown in the drawings.

The operation of the apparatus when the switch occupies its reverse position and a train trails the switch is similar to that which takes place when the switch occupies its normal position and a train trails the switch, and it is believed, therefore, that this operation will be readily understood from the foregoing and from an inspection of the drawings without further detailed description.

The tie rod 8 may be located at any suitable location between the heel and the toe of the switch but will preferably be located in such a position that the movable rails of the switch at the point where the tie rod is connected with them will not be forced from either extreme position to the other extreme position by a trailing train until

after the train has first caused the switch points to open. The reason for locating the tie rod 8 in such a position is to insure that after the switch points have become unlocked by a trailing train 5 forcing the roller 89 out of one inclined end or the other of the cam slot 88 and into the central portion of the cam slot, the cam plate will not continue to move far enough to permit the roller 89 to enter the opposite end of the cam slot and 10 cause the switch to become relocked before the switch points are forced open.

It should be particularly pointed out that with the apparatus constructed in the manner described if the linkage which connects the locking device with the tie rod 8 should get out of adjustment or develop lost motion for any reason, the locking device would either be prevented from moving to its proper locking position, or would be moved beyond its proper locking position, when the movable rails were moved to their proper normal or reverse positions, and since the circuit controller C includes means for indicating when the locking device is in its proper locking position under these conditions, the circuit controller would then give an indication that the parts were not in proper working order, thus avoiding any possibility of a dangerous condition existing.

Referring now to Figs. 5 and 6, I have here shown a modified form of linkage for connecting the locking device 60 with the tie rod 8. As here illustrated, the link 83 instead of being connected with the U-shaped member 84, as shown in Fig. 1, is pivotally connected with one end of a lever 97 which is pivotally mounted intermediate its ends on a pin 100 mounted in two spaced plates 101 and 102 secured to the bed plate 15. The free end of the lever 97 is provided with a roller 103 which cooperates with two spaced notches 104 and 105 provided in a cam plate 106. The cam plate 106 is guided for longitudinal sliding movement between rollers 107 mounted on pins journaled in the plates 101 and 102, and is secured at the end next the rail 1 to the previously described connecting rod 94. The parts are so proportioned that the roller 103 will enter the notch 104 when and only when the movable rails of the switch occupy their proper normal position in which they are shown in the drawings, 50 and that the roller 103 will enter the notch 105 when and only when the movable rails of the switch occupy their proper reverse position. The parts are further so proportioned that when the roller 103 enters either the notch 104 or the notch 55 105, the plunger bolt 81 will then be moved toward the left to a position in which it will arrest the movement of the locking device 60 by the biasing springs 68 when the locking device has been moved to its normal locking position, but that, when the roller 103 is forced out of both of the notches 104 and 105, the plunger bolt 81 will then be moved toward the right to a position in which it holds the locking device 60 in its unlocking position. 65

The operation of the apparatus as a whole when the locking device 60 is connected with the tie rod 8 by means of the modified form of linkage shown in Figs. 5 and 6 is similar to that previously described when the locking device 60 is connected with the tie rod 8 by means of the linkage shown in Figs. 1 and 4, and it is believed, therefore, that the operation of the apparatus as a whole when constructed as shown in Figs. 5 70 and 6 will be readily understood from the fore-

going description and from an inspection of the drawing without further detailed description.

One advantage of apparatus embodying my invention is that it provides simple means for locking a spring switch in both extreme positions of the switch for facing point moves over the switch in such manner that when a train trails the switch, the switch will become automatically unlocked until the train has completely passed the switch, after which the switch will become relocked, and at the same time insures that the switch will not become improperly locked when it is moved from one extreme position to another extreme position by a trailing train. 5 10

Although I have herein shown and described only two forms of railway switch operating apparatus embodying my invention, it is understood that various changes and modifications may be made therein within the scope of the appended claims without departing from the spirit and 15 scope of my invention. 20

Having thus described my invention, what I claim is:

1. In combination, a spring switch, means for actuating said switch between its two extreme 25 positions, locking means biased to a single locking position and movable to its locking position when and only when said switch occupies an extreme position corresponding to the position of said switch actuating means and effective when 30 moved to its locking position for locking the switch in the extreme position which it then occupies, and means mechanically actuated by a train trailing said switch in either extreme position of the switch for actuating said locking 35 means from its locking position to an unlocking position to unlock the switch until after the train has completely passed the switch.

2. In combination, a spring switch, means for actuating said switch between its two extreme 40 positions, locking means biased to a single locking position and movable to its locking position when and only when said switch occupies an extreme position corresponding to the position of 45 said switch actuating means and effective when moved to its locking position for locking the switch in the extreme position which it then occupies, and means responsive to the lateral bending of the rails which takes place when a train trails the switch in either extreme position of 50 the switch before a sufficient force is developed at the points of the rails to move the closed point away from the associated fixed rail for actuating said locking means from its locking position to an unlocking position to unlock the switch until 55 after the train has completely passed the switch.

3. In combination, a spring switch, means for actuating said switch between its two extreme 60 positions, locking means biased to a single locking position and movable to its locking position when and only when said switch occupies an extreme position corresponding to the position of 65 said switch actuating means and effective when moved to its locking position for locking the switch in the extreme position which it then occupies, a tie rod connecting the rails at a point intermediate the heel and the point of the switch, and means connecting said tie rod and said locking means and effective when a train trails the switch in either extreme position of the switch 70 for actuating said locking means to unlock the switch while the train is trailing the switch.

4. In combination, a spring switch, means for actuating said switch between its two extreme 75 positions, locking means biased to a single lock-

- ing position and movable to its locking position when and only when said switch occupies an extreme position corresponding to the position of said switch actuating means and effective when 5 moved to its locking position for locking the switch in the extreme position which it then occupies, a tie rod connecting the rails at a point intermediate the heel and the point of the switch, and means connecting said tie rod and 10 said locking means and responsive to the lateral bending of the rails which takes place when a train trails the switch in either extreme position of the switch before a sufficient force is developed at the points of the rails to move the 15 closed point away from the associated fixed rail for actuating said locking means from its locking position to an unlocking position to unlock the switch until after the train has completely passed the switch.
- 20 5. In combination, a railway switch, means for actuating said switch between its two extreme positions, means for biasing said switch to the extreme position to which it is moved by said switch actuating means, locking means biased to a single locking position and effective when the switch is moved to either extreme position by said switch actuating means for locking the switch in such extreme position, means mechanically actuated by a train trailing the switch in 25 either extreme position of the switch for actuating said locking means from its locking position to a position in which the switch is unlocked until the train has passed the switch, and means effective if the switch is moved from either 30 extreme position to the other extreme position by the trailing train for preventing the switch from becoming locked in such other extreme position.
- 35 6. In combination, a railway switch, means for actuating said switch between its two extreme positions, means for biasing said switch to the extreme position to which it is moved by said switch actuating means, locking means biased to a single locking position and effective when the switch is moved to either extreme 40 position by said switch actuating means for locking the switch in such extreme position, means mechanically actuated by a train trailing the switch in either extreme position of the switch for actuating said locking means from its locking position to a position in which the switch is unlocked until the train has passed the switch, and means controlled by the switch actuating means and effective if the switch is moved from either extreme position to the other extreme 45 position by the trailing train for preventing the switch from becoming locked in such other extreme position.
- 50 7. In combination with a spring switch, means for actuating said switch between its two extreme positions, a locking plunger biased to a locking position and movable to its locking position when and only when the switch occupies one or the other of its extreme positions and effective when in its locking position for locking the switch in the extreme position which it then occupies, means controlled by said switch actuating means for moving said locking plunger from its locking position to an unlocking position to unlock the switch prior to movement of the 55 switch by said switch actuating means, means mechanically actuated by a train approaching the switch in a trailing direction when the switch is locked in either extreme position by said locking plunger for moving said locking plunger from its locking position to its unlocking position until after the train is completely past the switch, and means for preventing said locking plunger from locking the switch in either extreme position in the event that the switch is moved to such extreme position by a trailing 60 train.
8. In combination with a spring switch, manually operable means for moving the switch between its normal and reverse positions, a locking plunger movable between a locking position and an unlocking position and biased to its locking position, a lock rod connected with the movable rails of said switch and provided with a normal notch which is adapted to receive said locking plunger when said switch occupies its normal position and said locking plunger is moved to its locking position and with a reverse notch which is adapted to receive said locking plunger when said switch occupies its reverse position and said locking plunger is moved to its locking position, means for moving said locking plunger from its locking position to its unlocking position prior to movement of said switch by said 65 manually operable means and for preventing said locking plunger from moving to its locking position except when said switch and said manually operable means occupy corresponding extreme positions, and means effective when said switch is locked in either extreme position and a train starts to trail the switch for moving said locking plunger from its locking position to its unlocking position to unlock said switch until after the train is completely past the switch.
9. In combination with a railway switch, a switch actuating shaft movable between two extreme positions and operatively connected with the switch for moving the switch between its normal and reverse positions, a star block rotatable about said shaft, means connected with said star block for biasing said star block to one position and for retarding movement of said star block by said biasing means, a manually operable lever rotatable in two planes, means responsive to rotation of said lever in one of said planes for rotating said switch actuating shaft between its two extreme positions, means responsive to rotation of said lever in the other plane for connecting said star block to and disconnecting it from said switch actuating shaft, a lock rod connected with the switch to move therewith and provided with a normal notch and a reverse notch, a locking plunger adapted to align with the normal notch or the reverse notch according as the switch occupies its normal or its reverse position and biased to a locking position in which it enters one or the other of said notches, means for moving said locking plunger in opposition to its bias to an unlocking position in which it is out of engagement with both the normal and reverse notches whenever said star block becomes disconnected from said switch actuating shaft, means connected with said locking plunger and adapted to be actuated by a train trailing the switch in either extreme position of the switch for moving said locking plunger from its locking to its unlocking position until after the train has completely passed the switch, and means controlled by said star block for preventing said locking plunger from moving to its locking position in the event the switch is moved from either extreme position to the other by a trailing train.
10. In combination with a railway switch, a switch actuating shaft movable between two extreme positions and operatively connected with

the switch for moving the switch between its normal and reverse positions, a star block rotatable about said shaft, means connected with said star block for biasing said star block to one position and for retarding movement of said star block by said biasing means, a manually operable lever rotatable in two planes, means responsive to rotation of said lever in one of said planes for rotating said switch actuating shaft between its two extreme positions, means responsive to rotation of said lever in the other plane for connecting said star block to and disconnecting it from said switch actuating shaft, a lock rod connected with the switch to move therewith and provided with a normal notch and a reverse notch, a locking plunger adapted to align with the normal notch or the reverse notch according as the switch occupies its normal or its reverse position and biased to a locking position in which it enters one or the other of said notches, means for moving said locking plunger in opposition to its bias to an unlocking position in which it is out of engagement with both the normal and reverse notches whenever said star block becomes disconnected from said switch actuating shaft, a tie rod connecting the movable rails of the switch at a point between the heel and the point of the switch, linkage connecting said tie rod and said locking plunger and effective when the switch occupies either extreme position and a train trails the switch for moving said locking plunger from its locking position to its unlocking position, and means controlled by said star block for preventing said locking plunger from moving to its locking position in the event the switch is moved from either extreme position to the other by a trailing train.

11. In combination with a railway switch, a switch actuating shaft movable between two extreme positions and operatively connected with the switch for moving the switch between its normal and reverse positions, a star block rotatable about said shaft, means connected with said star block for biasing said star block to one position and for retarding movement of said star block by said biasing means, a manually operable lever rotatable in two planes, means responsive to rotation of said lever in one of said planes for rotating said switch actuating shaft between its two extreme positions, means responsive to rotation of said lever in the other plane for connecting said star block to and disconnecting it from said switch actuating shaft, a lock rod connected with the switch to move therewith and provided with a normal notch and a reverse notch, a locking plunger adapted to align with the normal notch or the reverse notch according as the switch occupies its normal or its reverse position and biased to a locking position in which it enters one or the other of said notches, means for moving said locking plunger in opposition to its bias to an unlocking position in which it is out of engagement with both the normal and reverse notches whenever said star block becomes disconnected from said switch actuating shaft, a tie rod connecting the movable rails of the switch at a point between the heel and the point of the switch, linkage connecting said tie rod and said locking plunger in such manner that said locking plunger is free to move from its locking position to its unlocking position independently of any movement of said linkage but that when said switch occupies either extreme position and a train

trails the switch the lateral bending of the movable rails which takes place before sufficient force is exerted on the movable rails to cause the point of the movable rail which is then engaging the associated fixed rail to move out of engagement with the associated fixed rail will cause said locking plunger to move from its locking position to an unlocking position, and means controlled by said star block for preventing said locking plunger from moving to its locking position in the event that the switch is forced to an extreme position by a trailing train.

12. In combination with a spring switch, means for actuating the switch between its two extreme positions, locking mechanism for locking the switch in both of its extreme positions including a locking plunger constantly biased to a locking position, means for moving said locking plunger from its locking position to an unlocking position prior to movement of said switch by said switch actuating means, a tie rod connecting the movable rails of said switch, a cam plate operatively connected with said tie rod, and means controlled by said cam plate for moving said locking plunger from its locking position to an unlocking position when a train trails the switch.

13. In combination with a spring switch, means for actuating the switch between its two extreme positions, locking mechanism for locking the switch in both of its extreme positions including a locking plunger constantly biased to a locking position, means for moving said locking plunger from its locking position to an unlocking position prior to movement of said switch by said switch actuating means, a tie rod connecting the movable rails of said switch, a cam plate operatively connected with said tie rod, and means controlled by said cam plate for controlling said locking plunger.

14. In combination with a spring switch, means for actuating the switch between its two extreme positions, locking mechanism for locking the switch in both of its extreme positions including a locking plunger constantly biased to a locking position, means for moving said locking plunger from its locking position to an unlocking position prior to movement of said switch by said switch actuating means, a tie rod connecting the movable rails of said switch, a cam plate operatively connected with said tie rod in such manner that said cam plate will be moved to one position or another according as said switch is moved to its one extreme position or its other extreme position, said cam plate being provided with a cam slot having an intermediate portion which is parallel to the direction of movement of said cam plate and two end portions which are inclined to the direction of movement of said cam plate, a member carrying a roller disposed in said cam slot for cooperation therewith, and linkage connecting said member and said locking plunger, the parts being so proportioned that when said roller engages said cam slot at either inclined end of the slot said locking plunger is free to move to its locking position but that when said roller engages said cam slot at the intermediate straight portion said locking plunger will be moved to its unlocking position by said linkage.

15. In combination with a spring switch, means for actuating the switch between its two extreme positions, locking mechanism for locking the switch in both of its extreme positions including a locking plunger constantly biased to

- 5 a locking position, means for moving said locking plunger from its locking position to an unlocking position prior to movement of said switch by said switch actuating means, a tie rod connecting the movable rails of said switch, a cam plate operatively connected with said tie rod in such manner that said cam plate will be moved to one position or another according as said switch is moved to its one extreme position or 10 its other extreme position, said cam plate being provided with two notches, a lever pivotally supported intermediate its ends and provided at one end with a roller which is adapted to enter the one notch when the cam plate occupies one position and the other notch when the cam plate occupies the other position, and linkage connecting said locking plunger and the free end of said lever so proportioned that said locking plunger will be prevented from moving to its locking position except when said roller enters one or the other of said notches in said cam plate.
- 15 10 15 20 20 25 25
16. In combination with a spring switch, means for actuating the switch between its two extreme positions, locking mechanism for lock-
- ing the switch in both of its extreme positions including a locking plunger constantly biased to a locking position, means for moving said locking plunger from its locking position to an unlocking position prior to movement of said switch by said switch actuating means, a tie rod connecting the movable rails of said switch, a cam plate operatively connected with said tie rod in such manner that said cam plate will be moved to one position or another according as said switch is moved to its one extreme position or its other extreme position, said cam plate being provided with two notches, a member provided with a roller which is adapted to enter the one notch when and only when the cam plate occupies the one position and the other notch when and only when the cam plate occupies the other position, and means for connecting said member with said locking plunger in such manner that said locking plunger will be prevented from moving to its locking position except when said roller enters one or the other of said notches in said cam plate.

WALTER L. STOUT. 25
